UNITED STATES PATENT OFFICE.

MICHAEL ZIPPLER, OF ALLEGHENY, PENNSYLVANIA.

CUPOLA-FURNACE.

SPECIFICATION forming part of Letters Patent No. 638,541, dated December 5, 1899.

Application filed October 20, 1898. Serial No. 694,135. (No model.)

To all whom it may concern:

Be it known that I, MICHAEL ZIPPLER, a citizen of the United States, residing at Allegheny, in the county of Allegheny and State of Pennsylvania, have invented a certain new and useful Improvement in Cupola-Furnaces, of which the following is a specification.

My invention relates to cupola-furnaces, and has special reference to the formation of the linings in such furnaces.

One object of my invention is to provide a simple and effective lining for cupola-furnaces which will prevent the clogging of the material within the furnace after the metal has been run out of the furnace, and, further, to prevent the molten metal from running into the air-flues and burning out the lining and clogging the air-flues.

Another object of my invention is to provide such a lining which can be easily and rapidly constructed and repaired and will prevent the rapid burning out of the same by the intense heat, as well as one which is cheap and simple in its construction and will assist in the more rapid melting of the iron therein.

A further object of my invention is to provide such a form of lining as will prevent the cinder, metal, &c., from adhering to the lining and so do away with the possible breaking or chipping of the ordinary brick lining during the cleaning or removal of said cinder, metal, &c., therefrom.

My invention consists, generally stated, in the novel arrangement, construction, and combination of parts, as hereinafter more specifically set forth and described, and particularly pointed out in the claims.

To enable others skilled in the art to which my invention appertains to construct and use the lining, I will describe the same more fully, referring to the accompanying drawings, in which—

Figure 1 is a vertical central section of the base portion of a cupola-furnace, showing my improved lining applied thereto. Fig. 2 is a cross-section of the same on the line 2 2, Fig. 1, showing some of the parts in full lines. Fig. 3 is a detail cross-section on the line 3 3, Fig. 1. Fig. 4 is a detail cross-section on the line 4 4, Fig. 1. Fig. 5 is a perspective view of one of the metal blocks, and Fig. 6 is a per-

spective view of one of the metal bricks or plates.

Like letters herein indicate like parts in each of the figures of the drawings.

The cupola-furnace is shown at A, and is provided with the ordinary sheeting or casing a, inclosing the lining b, which is generally formed of fire-brick and of the same general thickness of walls throughout the length or height of the furnace A. Casing a and lining d of the cupola A are built up from the bottom plate c, which rests upon columns d, extending down to the ground or floor of the foundry or mill for supporting the cupola A. The bottom plate c is preferably formed in four pieces and has an opening c' therein, which is closed by the doors c², hinged at c³ to each side of the bottom c and forms the bottom or base of the cupola A for supporting the material within the same and permitting the withdrawal of said material contained within the cupola A after the heat or when desired. At the bottom of the cupola A, adjacent to the bottom plate c, is the ordinary tap-hole c⁴, which extends through the casing a and lining b, and is adapted to draw off the molten metal from the interior of the cupola A. In the present construction the lining b is built up from the bottom plate c for a short distance of uniform thickness to form the wall f, upon which is secured the lower metal ring g, which is formed in segmental plates or sections g'. Resting upon the metal ring g are a series of metal blocks h, which are placed around the ring g, so as to form the spaces or flues h' between them and the space or flue h² between the rear of the block h and the casing a for the circulation of air to the interior of the cupola A from air-pipes i' opening into the interior of the cupola A from the main blast-pipe i on the exterior of the cupola A. These metal blocks h are provided with curved faces h³, corresponding to the interior curved line of the ring g and the recesses h⁴ on the rear of the same for more properly distributing the air from the air-pipes i' to the interior of the cupola A. Another metal ring j, formed in segmental plates or sections j', is laid or secured upon the metal blocks h for supporting the metal bricks or plates k, which are tapered on their

sides, as at k' , so as to form a brick or plate of keystone or wedge shape for insertion to form the circular metal lining b' at that point. The bricks or plate k are inclined upwardly 5 and inwardly toward the center of the cupola A on their front faces k^2 , as at k^3 , and, if desired, the plates k can be recessed on their rear faces k^4 for the purpose of decreasing the weight of the same. The metal bricks or 10 plates k are also provided with top faces k^6 and bottom faces k^7 , and upon the top faces k^6 rests the upper metal ring l , which is formed in plates or sections l' and supports the lining b^2 of the lining b . This lining b^2 15 is preferably of ordinary fire-brick and extends from the inner edge of the metal ring l backward and upward on an incline, as at b^3 , toward the upper lining b^4 of the lining b to form the inward projecting portion b^5 of 20 the lining b , and this upper lining b^4 being preferably formed of fire-brick of a thickness about four and one-half ($4\frac{1}{2}$) inches from the lining b^2 up to the top of the cupola A.

The manner of constructing and operating 25 my improved cupola-furnace A is as follows: The wall f , forming part of the lining b , is built up from the bottom plate c to the required distance within the casing a , and the segmental plates g' to form the lower metal 30 ring g are placed upon and secured to the top of said wall f , after which the metal blocks h are placed in position upon the ring and the required distance apart to form the flue h' and flue h^2 . The segmental sections, 35 comprising the middle metal ring j , are then placed upon and secured over the metal blocks h , and this ring j is firmly secured to the metal bricks or plates k , which are set to form the circular metal lining b' , so that the inner 40 edge of the bottom faces k^7 rest flush with the inner edge of the ring j . The plates or bricks k , being of wedge shape, are set side by side and firmly secured in place to form the lining at the point in the furnace A where the greatest 45 heat is maintained. The segmental sections l' , comprising the ring l , are then placed upon the metal bricks k , with their inner edges flush with the upper edge of the inclined faces k^3 on the front face k^2 of the bricks 50 k , and upon this ring l is built up the lining b^2 of the lining b . This lining b^2 is inclined backward from the edge of the ring l to form the inwardly-projecting portion b^5 , and upon this lining b^2 is built the upper wall or lining 55 b^4 , running to the top of the cupola A. The sand, coke, &c., are placed upon the doors c^2 , within the cupola A, and said material extends up to about the top of the lining b^2 , where the metal to be melted is placed. The 60 fire having been started within the cupola A and actuated by the blast from the air-pipes i , the metal will be caused to melt and run down the lining b^2 through the coke to the bottom of the cupola A away from the air- 65 flues h' , where it can be drawn off through the tap-hole c^4 . After the metal has been

melted and drawn off through the tap-hole c^4 the doors c^2 can be opened and the material left within the cupola A will be free from the lining b , so as to be dropped to the ground or 70 floor.

It will thus be seen that my improved cupola-furnace lining is cheap and simple, and its construction and practical experience have proved that it will prevent the clogging of the 75 material within the furnace and the running of the metal into the air-flues, so prolonging the life of the lining and the furnace, and thus saving labor, time, and expense in the operation of these furnaces. It will also be 80 seen that by the use of this particular kind of lining it will prevent the cinder, metal, &c., from adhering thereto, as in the ordinary brick lining, and so do away with all liability of the breaking or chipping of the same during the 85 cleaning out or removing of said adhering substance, as in the case of brick lining.

What I claim as my invention, and desire to secure by Letters Patent, is—

1. A cupola-furnace having its lining 90 formed with an inwardly-projecting fire brick or clay portion at the base thereof, and a metal lining below the same extending backwardly or outwardly from the edge of said projecting portion.

2. A cupola-furnace having its lining formed with an inwardly-projecting fire brick or clay portion at the base thereof, and an outwardly-flaring metal portion below the 100 same.

3. A cupola-furnace having its lining formed with an inclined fire brick or clay portion extending downwardly toward the interior of the furnace at the base portion thereof and an outwardly-flared metal portion below 105 the same.

4. A cupola-furnace having its lining formed with an inclined fire brick or clay portion extending downwardly toward the interior of the furnace at the base portion thereof, and a series of metal bricks forming an outwardly-flared lining under said inclined portion.

5. A cupola-furnace having its lining formed with an inclined fire brick or clay portion extending downwardly toward the interior of the furnace at the base thereof, a series of metal bricks forming an outwardly-flared lining under said inclined portion, and a series of metal blocks under said metal 120 bricks, having air-spaces between them.

6. A cupola-furnace having its lining formed with an inclined fire brick or clay portion extending downwardly toward the interior of the furnace at the base thereof, a series of metal bricks forming an outwardly-flared lining under said inclined portion, and a metal plate or ring between said downwardly-extending inclined portion and said metal bricks.

7. A cupola-furnace having its lining formed with an inclined fire brick or clay por-

tion extending downwardly toward the interior of the furnace at the base thereof, a series of metal bricks forming an outwardly-flared lining under said inclined portion, a series of metal blocks under said metal bricks having air-spaces between them, and a metal plate or ring between said metal bricks and metal blocks.

8. A cupola-furnace having its lining formed with an inclined fire brick or clay portion extending downwardly toward the interior of said furnace at the base thereof, a metal ring under said inclined portion, a series of metal bricks forming an outwardly-

flared lining under said metal ring under 15 said metal bricks, a series of metal blocks forming air-spaces between them, and a metal ring between said metal blocks and the base-lining.

In testimony whereof I have hereunto set 20 my hand, at Pittsburg, in the county of Allegheny and State of Pennsylvania, this 24th day of September, A. D. 1898.

MICHAEL ZIPPLER.
